UNITED STATES PATENT OFFICE.

EDWIN F. HULBERT, OF MILWAUKEE, WISCONSIN, ASSIGNEE, BY MESNE ASSIGNMENTS, TO THE MASTER PACKAGE CORPORATION OF DELAWARE.

FIBER CONTAINER.

Application filed October 12, 1925. Serial No. 62,029.

The invention relates to fiber containers and to a method of making the same.

The object of the invention is to provide a closure for, and a method of attaching this closure to, the fiber siding forming the cover or body of the container, whereby the head is firmly secured to the siding and to a metal band which is clamped over the head with a part of the siding.

10 The invention further consists in the several features hereinafter set forth and more particularly defined by claims at the conclusion hereof.

In the drawings, Fig. 1 is a perspective view of a closure embodying the invention, parts being broken away and parts being shown in section;

15 Fig. 2 is a detail sectional view showing the initial position of the container parts;

20 Fig. 3 is a view similar to Fig. 2, showing an intermediate step in the method of attaching the closure;

25 Fig. 4 is a sectional view through the container closure when the assembling process is completed.

The numeral 5 designates the fiber siding of the container, which may be of pressed pulp or a number of wrappings of fiber or paper sheets, and is generally a cylindrical or conical section.

30 The numeral 6 designates the fiber head, usually made up of a number of laminations of paper or fiber sheets.

The numeral 7 designates a band of thin sheet-steel, or other suitable sheet-metal, which is formed to provide annular head-receiving spaced flanges 8 and 9, and a part 10 with a slightly curved upper edge 10' extends outwardly from the inner edge of

40 the flange 9.

The head 6, with the band 7 attached thereto, is inserted into the siding 5 so that it rests on an anvil 11 which engages said siding 5, and a clamping plunger 12 is

45 moved down against the head to hold it firmly against the anvil 11, as shown in Fig. 2. An external contractible chuck 13, whose parts have straight cylindrical surfaces 14

50 and a siding-engaging surface 15 offset from the surface 14 and joined thereto by a curved

surface 16, is moved inwardly against the siding from the position shown in Fig. 2 to that shown in Fig. 3. This has the effect of bending over the extended end 17 of the siding against the flange 9.

55

With the parts thus formed a forming plunger 18, having an annular part 19 working in the space between the contracted chuck 13 and the plunger 12 and provided with a semicircular curved edge 20, is then 60 moved down between the chuck 13 and the plunger 12, and during the first part of its movement it bends the edge 10' of the band over the inturned extension 17 of the siding and thereafter by continued longitudinal 65 pressure this is curled with the edge of the extension 17 of the siding into convolute form and at the same time a part 21 of said siding extension is forced down against the flange 9 and the flanges 8 and 9 pressed 70 against the head and the head is thus firmly held in place between the parts of the band and the inturned edge of the siding which, with the band, provides a very strong abutment to resist loads tending to force the 75 head outwardly from the siding.

A facing 22 of paper may also be secured to the head and over the flange 8 when it is desired to prevent contact of the contents of the container with the metal band.

80

What I claim as my invention is:

1. In a fiber container, the combination with the fiber siding and the fiber head, of a sheet-metal band having spaced flanges receiving the head and a part extending 85 from the inner edge of the outer flange and extending over a part of the siding projecting over the head.

2. In a fiber container, the combination, with the fiber siding and the fiber head, of a sheet-metal band having spaced flanges receiving the head and a part extending from the inner edge of the outer flange over a part of the siding extending inwardly 95 over the head and having its outer edge curled with the outer edge of the siding into a beaded edge.

In testimony whereof, I affix my signature.

EDWIN F. HULBERT.
